UNITED STATES PATENT OFFICE.

THOMAS F. WRIGHT AND ED. G. WILSON, OF CHICAGO, ILLINOIS.

INDUCTION-PREVENTIVE FOR TELEPHONES.

SPECIFICATION forming part of Letters Patent No. 447,858, dated March 10, 1891.

Application filed July 28, 1890.

Serial No. 360,165. (No model.)

To all whom it may concern:

Be it known that we, THOMAS F. WRIGHT and ED. G. WILSON, both of Chicago, county of Cook, and State of Illinois, have invented 5 certain new and useful Improvements in Induction-Preventives for Telephones, of which the following is a specification.

This invention relates to improvements in induction - preventives for telephones, but 10 more especially to that class in which the device is attached to the receiver.

Prior to this invention numerous devices have been invented for preventing induction in telephones, but so far as we are aware 15 none of such devices have been practically successful when subjected to the ordinary conditions under which they must operate; but our invention has been practically tested under all the usual conditions and proved 20 both operative and successful, the prime object thereof being to prevent induction without materially or injuriously reducing the strength of the talking-current.

Another object is to have the device of such 25 a character that it is readily attachable to and adapted for use in connection with the ordinary "hand phones" or receivers now in use.

These objects are attained by the devices 30 illustrated in the accompanying drawings, in which—

Figure 1 represents a side elevation of an ordinary telephone-receiver of the Bell pattern, having an induction device applied 35 thereto embodying my invention; Fig. 2, a central longitudinal section thereof; Fig. 3, a face view of the induction device detached from the receiver, and Fig. 4 a side elevation thereof.

Similar letters of reference indicate the 40 same parts in the several figures of the drawings.

Referring by letter to the accompanying drawings, A indicates a casing preferably composed of sheet metal, having the external appearance of a small cup or bowl, of such dimensions and contour as to fit snugly within the concavity or depression in the end of the receiver, as more clearly illustrated in Fig. 2, 45 the face or interior portion of the casing, however, having preferably an irregular shape, being concaved around the outer portion or

edges of the cup and provided with a central projecting portion or dome B, intended to fit against and within the ear, which latter will 55 be practically covered by the casing when applied thereto. The two walls of the casing—that is, the front and back thereof—are provided with central perforations C D, between which a practically-continuous passage is 60 formed by the insertion of a tube E of any suitable material, but which is, preferably, composed of a coil of small steel wire, which in practice has proven to produce the most desirable results, although we are not prepared to state that other forms of tubes and other material cannot be employed with equally good results. Surrounding this tube, but inclosed within the casing, is a spool F, 65 preferably of wood, of any suitable shape or 70 dimensions, the most desirable being that conforming to the interior of the casing. This spool is grooved externally, as shown, and has wound thereon a coil of fine wire G, copper being found to produce the desired results, 75 one end of which H is inserted or driven into the spool, while the other end I terminates immediately in front of, but preferably out of contact with, the diaphragm J of the telephone-receiver, which latter may, 80 if desired, be perforated at the center immediately opposite the terminal of the coil, as shown at K, which we have found in some instances to promote the effectiveness of the device, while in others the perforation could 85 be dispensed with, sometimes without changing and sometimes promoting the results.

This induction device may be attached to the receiver in any suitable manner either by the spring-hook L, attached to the casing 90 A, engaging the usual flange upon the end of the receiver, or by any other device which will accomplish the desired result.

In practice we have found it most desirable, if not essential, that the wooden spool 95 F be kept at all times in a perfectly-dry condition, and to this end we have usually dipped the spool in melted paraffine after the coil has been wound thereon, thus effectually insulating the same against dampness; but other 100 means may be employed for accomplishing the same end without departing from the spirit of this invention.

It has also been our practice to have the

wire forming the coil G covered with an insulating-wrapping of some kind, so as to electrically insulate the coils from each other and from the casing, the extreme free ends H and I only being exposed or without insulation.

So far as we are aware the shape or the dimensions of the casing, as well as of the core, is immaterial, and may be made of any suitable form and size best adapted for the intended uses, nor is it absolutely essential that the spool surround the tube or that the coil be wound upon a spool, so long as the inner end H thereof is embedded in or otherwise connected with a block of wood or other equivalent for the coil, the arrangement herein shown, however, being the most advantageous and convenient known to us, nor are we prepared to state the theory of operation of this device, but simply that it does operate to absolutely prevent induction under all ordinary conditions, and that its operativeness has been practically tested and demonstrated.

Having described our invention, what we claim, and desire to secure by Letters Patent, is—

1. An induction-preventive for telephones, comprising a hollow casing having perforations therein, a tube extending between said perforations, and a coil one end of which is embedded in a spool or block of wood or its equivalent and the other terminates opposite the center of a perforation in the casing opposing the diaphragm of a telephone-receiver to which the casing is secured, substantially as described.

2. An induction-preventive for telephones, comprising a hollow casing provided with perforations, a tube consisting of a coil of metallic wire extending between said perforations, and a coil one end of which is embedded in a spool or block of wood or its equivalent.

lent and the other terminates opposite the center of a perforation in the casing opposing the diaphragm of a telephone-receiver to 45 which the casing is secured, substantially as described.

3. An induction-preventive for telephones, comprising a hollow casing provided with perforations, a tube extending between said 50 perforations, a spool located within said casing, and a coil of wire wound upon said spool, one end of which is embedded in the spool and the other terminates opposite the center of a perforation in the casing opposing the 55 diaphragm of the receiver to which the device is secured, substantially as described.

4. An induction-preventive for telephones, comprising a hollow casing provided with perforations, a tube consisting of a coil of metallic wire 60 extending between said perforations, a spool located within said casing, and a metallic coil wound thereon, one end of which is embedded in the spool and the other end terminates opposite the center of the perforation in the casing opposing the diaphragm 65 of the telephone-receiver to which the device is secured, substantially as described.

5. The combination, with a telephone-receiver and the diaphragm thereof provided with a central perforation, of an induction-preventive comprising a hollow casing provided with perforations, a tube extending between said perforations, a spool located within said casing, and a metallic coil wound 75 upon said spool, one end of which is embedded in the spool and the other terminates opposite the center of the perforation in said diaphragm, substantially as described.
